UNITED STATES PATENT OFFICE.

TIMOTHY W. MURPHY, OF WASHINGTON, DISTRICT OF COLUMBIA.

RAIL-CHAIR.

SPECIFICATION forming part of Letters Patent No. 601,584, dated March 29, 1898.

Application filed July 23, 1897. Serial No. 645,683. (No model.)

To all whom it may concern:

Be it known that I, TIMOTHY W. MURPHY, of Washington, in the District of Columbia, have invented certain new and useful Improvements in Rail-Chairs; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to certain new and useful improvements in rail joints and chairs, and has for its objects simplicity, durability, and cheapness in construction, composed of a minimum number of parts, and sure, quick, and effective in operation.

A further object of the invention is to provide a chair which can be easily and quickly set without the use of fish-plates, screws, bolts, or nuts, and one that can be equally as well used with either a metal or wood tie.

A further object of the invention is to provide a chair so constructed that where the several members join the said joints are protected against interference of malicious persons, the working parts all being under cover and out of sight, the opening in the tie being under the chair; or two ties may be used, leaving a space between them. The working parts in this space or opening are hidden from view, and no person can know how they are fastened until he possesses the key to their operation, and they are so arranged and interlocked that they assist each other to hold their proper positions and can only be removed in the proper way.

The invention consists in certain novel features of construction and in combinations of parts more fully described hereinafter and particularly pointed out in the claims.

In the accompanying drawings, Figure 1 is a central vertical cross-section through one rail, showing the invention applied to a wood tie, as on the line $x-x$ of Fig. 3. Fig. 2 is a similar view taken on a line to either side of Fig. 1, as on line $y-y$ of Fig. 3. Fig. 3 is a top plan view of the chair or base-plate applicable to one line of rail, but when desired continued to the other line of rail, forming a metallic tie. Fig. 4 is an elevation of the inter-

locking clamps and brace-plates in operative position, but removed from the tie, the rail not shown. Fig. 5 is an inverted detail perspective view of the locking-plate. Figs. 6 and 7 are detail perspective views of the interlocking clamps.

Referring by letter to the drawings, a is the base-plate or metallic tie, which is adapted to be used either alone or in connection with a wood tie b .

c is a depression or recess for the reception of the rails d .

About the center of the base-plate or metallic tie a is a slot e , to each side of which are the openings e' .

Below the slot e on the under side of the plate or tie a and inside the rail depression c or between the tracks is a box or frame e^2 , depending from said tie a to receive the interlocking clamp g' . An opening e^3 is provided for the reception of the king-pin f , which is forced down through said clamp g' and opening e^3 when the chair is set. 75

g and g' are the interlocking clamps, having the depending posts h h' , adapted to fit into the slot e and openings e' , the post h fitting the central slot e , the lips h^2 resting in the recess e^4 , and the edge of the brace-plate g snugly 80 abutting the bevel bead or stay g^2 . The short posts h fit the openings e' , and the lips e^3 rest in the recesses e^4 , thus forming a tongue-and-groove joint.

Passing inwardly and snugly fitting the slot 85 e and flush with the top surface of the depression c is a tongue i , which rests on the support j of the depending block j' of the brace-plate or the inside member of the interlocking clamp g' and is held there by the pressure 90 of the rail d . The block j' also has an inwardly-projecting tongue j^2 , which fits in the slot e and rests on the box or frame e^2 , having an opening j^3 , corresponding with the opening e^3 , through which passes the king-pin f , 95 thereby securing the rail d rigidly between the interlocking clamps g g' and the base-plate or metallic tie a .

k is the locking-plate, adapted to fit in the opening l of the plate or tie a , having offsets 100 corresponding and registering with the depressions around said opening l to prevent the insertion of a tool for prying the plate up. This plate is also provided with an extension

m, which fits over and is adapted to secure the clamp *g*.

m' is a frame in which the extension *m* snugly fits for the purpose of preventing tampering.

On the under side of the locking-plate *k* is a downwardly-projecting leg *k'*, which rests in the curved end of the tongue *j*² of the clamp *g* and presses same tightly against the rail.

Any suitable lock may be employed to secure the locking-plate *k* to the tie; but I preferably use a dovetail joint consisting of the dovetail or tapering lugs *n* and a beveled bar (not shown) which coincides with and is adapted to slide between and be tightly held by said lugs *n*, or the lock *v* and key *w* may be employed, the lock being secured in the tie below the locking-plate and the key passing up therethrough and operated from above said locking-plate.

This chair is adapted to be used either with metallic or wood ties, and it is constructed without the use of screws, bolts, or nuts; but when the base-plate or metallic tie *a* is used alone suitable pins *p* are employed to pass through the clamp *g* and said tie *a*, beneath which and through the pin *p* is passed a split key *p'*.

The construction and operation of this chair is very simple and is as follows:

The clamp *g* is set in position on the outside of the rail on the base-plate *a*, the depending posts *h* and *h'* inserted into the slot *e* and the openings *e'*, the openings *e'* being of sufficient length to allow the lips *h*² and *h*³ to pass down low enough to slide into the recesses *e*⁴ of the metallic tie or base-plate *a* and the edge of the base-plate pressing against the bead *g*², the tongue *i* being flush with the depression *c* in said tie or plate. The adjacent ends of the rails *d* are then placed in the depression *c* on the tongue *i*, the base of the rail being beneath the brace-plate of the clamp *g*. The clamp *g'* is then set in place, the depending legs *j* passing into the slot *e*, and pushed toward the rail, the brace-plate pressing tightly against the rails *d*, fitting snugly between the head and base thereof. The support *j* is carried directly under the tongue *i* of the clamp *g*, the tongue *j*² resting in the frame or box *e*², the openings *e*³ of the box and *j*³ of the tongue *j*² registering and adapted to receive the king-pin *f*. When the king-pin *f* is in place, it is readily seen that the rail is rigidly held between the two clamping-plates *g* and *g'* and the metallic tie or base-plate *a*. The locking-plate *k* is then adjusted in the opening *l*, bearing directly on the tongue *j*² and the upward extension *m* thereof on the brace-plate between the frame *m'*. The leg *k'* of the locking-plate *k* rests in the curved end of the tongue *j*², and when the beveled or dovetailed bar is inserted in the way formed by the dovetailed lugs *n*, carried by the metallic tie or base-plate *a*, it is impossible to raise said locking-plate *k* or the king-pin *f*. Hence the whole is securely held

and interlocked as rigidly as a single piece of metal. This construction of interlocking clamps may be used to as much advantage in other structures than rail-chairs—for instance, such as bridges, towers, buildings, &c.

It is evident that various changes might be made in the forms, construction, and arrangements of the parts described without departing from the spirit and scope of the invention. Hence I do not wish to limit myself to the exact construction herein set forth, but consider myself entitled to all such changes as fall within the spirit of the invention.

Having thus fully described my invention, what I claim, and desire to secure by Letters Patent of the United States, is—

1. A rail-chair comprising, the base-plate 85 or metallic tie, having openings, clamps having depending posts, adapted to engage said openings, a box or frame beneath said base-plate having an opening and a pin adapted to pass through one of the clamps and the 90 frame, substantially as described.

2. A rail-chair comprising; the base-plate having a series of openings therein, a depression in the top of said base-plate, clamps having depending posts, lips on said posts engaging said openings, a tongue on one clamp, a support on the other clamp on which said tongue rests, a frame beneath said base-plate, the inside clamp resting in said frame, a pin passing through said frame and clamp and a 100 locking-plate resting on and covering said pin, substantially as described.

3. A rail-chair comprising, the base-plate, a central slot therein, openings in said plate, a depression in the top surface of said plate, 105 clamps having tongues, depending posts from said clamps having tongues engaging said slot and openings, a support on the inside clamp for the tongue of the outside clamp which is flush with the upper surface of the 110 depression in the base-plate for the reception of the rail, a tongue resting in the box or frame of the base-plate having an opening, an opening in said frame registering with said opening in the tongue adapted to receive 115 a pin, a locking-plate holding said pin in place and locking means for said locking-plate, substantially as described.

4. In a railroad-chair the combination, of the rail, the base-plate, the clamps interlocking therewith under the rail, a locking-plate and a king-pin arranged under the locking-plate securing the clamps in position, substantially as described.

5. A rail-chair consisting of the base-plate, 125 the interlocking clamps, the clamps locking beneath and held in position by the rail, a king-pin securing said clamps and a locking-plate securing said pin, substantially as described.

6. A railway-rail chair comprising, the base-plate or metallic tie, clamps interlocking therewith, the rail securing said clamps, brace-plates carried by said clamps, a king-pin pass-

ing through one of the clamps and a locking-plate which covers as a locking means the said pin, substantially as described.

7. A railroad-chair comprising, the base-plate having a series of openings therein, a depression in the top of said base-plate, clamps having depending posts engaging said openings, a tongue on one clamp, a support on the other clamp, on which said tongue 10 rests and the rail resting on said tongue to secure said clamps, substantially as described.

8. A railroad-chair consisting of the base-plate having a depression in its face to seat the rail, an upward-projecting bead or stay 15 for the clamp-support, a series of openings through its face for the depending portion of the clamp, and depressions or seats in its under side to receive said portions, a downwardly-projecting box or frame for the lateral tongue of the inside clamp, said box being provided with a locking-hole to receive the king-pin, when the clamps are in position, in combination with the rail-clamps, substantially as described.

25 9. A railroad-chair comprising a base-plate having a depressed seat for a rail, a longitudinal opening in its center, in combination with clamps provided with depending securing-lugs, said clamps having tongue projec- 30 tions at right angles to the clamps and adapted

to support and lock each other when in position as set forth.

10. A railroad-chair comprising the base-plate constructed as described, the clamping-jaws provided with depending securing-lugs 35 having lateral projections, and horizontal projecting locking-tongues adapted to lock the parts together when in position in the manner shown and described.

11. The combination in a railroad-chair of 40 the base-plate constructed as described, having the downwardly-projecting seat or box e^2 , of the inside clamping-jaw g' , the king-pin and the locking-plate k , having extension m adapted to rest in said box and lock the 45 jaws in position in the manner set forth.

12. The combination in a railroad-chair, of 50 the base-plate as shown, and provided with the downwardly-projecting box e^2 , of the locking-plate k , having extension m and leg k' arranged to hold the rail and clamps in position as shown and described.

In testimony that I claim the foregoing as my own I affix my signature in presence of two witnesses.
